ROTARY ENGINE

Samuel J. Collum, Philadelphia, Pa.

Application May 4, 1935, Serial No. 19,760

13 Claims. (Cl. 123—8)

My invention relates to a rotary fluid-pressure motor and it relates particularly to a motor which is adapted to use an explosive vapor such as vapor including gasoline or kerosene.

5 It is an object of my invention to construct a rotary motor wherein a substantially continuous force is applied as the driving force.

Another object of my invention is to construct an engine utilizing an expansive fluid which exerts 10 substantially a constant force upon a rotatable piston.

Another object of my invention is to construct 15 a rotary fluid pressure motor wherein the rotor has a high moment of inertia and is perfectly balanced to serve as a fly wheel.

Another object is to utilize the various mechanisms embodied in the motor so that its moment of inertia is relatively high and to dispense with a fly wheel.

20 Another object of my invention is to construct a motor wherein the elements may be easily assembled and disassembled when repairs or replacement of parts are necessary.

Another object of my invention is to construct 25 a rotary motor which will not require the conventional starting apparatus.

Another object is to construct a rotary motor so that the parts are symmetrically arranged to form a uniformly balanced rotor.

30 Another object is to construct a simple uniformly balanced piston of a single piece of material.

Another object of my invention is to construct 35 a motor which is readily adaptable to utilize various types of fuel.

Another object is to utilize a rotary circular piston which has its inner portion suitably supported by the members defining the toroidal bore.

Another object of my invention is to construct 40 a rotary motor wherein the inlet and discharge orifices or passageways are simple in construction and wherein the controls for the passageways are simple and inexpensive in construction.

A further object is to construct a rotary motor 45 which utilizes a fixed member as a barrier in the toroidal bore.

Other objects of my invention are to provide an improved device of the character described, that is easily and economically produced, that is 50 sturdy in construction, and which possesses a maximum degree of efficiency and of accuracy.

With the above and related objects in view, my invention consists in the details of construction and combination of parts, as will be more fully understood from the following description, when

read in conjunction with the accompanying drawings, in which:—

Fig. 1 is a side elevational view of my invention embodied in a rotary motor.

Fig. 2 is a perspective view of one of the supporting plates upon which the rotary piston is 5 suitably supported.

Fig. 3 is a perspective view of the rotary piston.

Fig. 4 is a perspective view of one of the hemispherical casings for the rotary motor. 10

Fig. 5 is a perspective view of an inner bushing upon which the plates, one of which is illustrated in Fig. 2, is fastened.

Fig. 6 is a perspective view of one of the walls which defines the chamber or bore wherein the 15 fluid may expand.

Fig. 7 is a perspective view of the second complementary plates which defines the chamber or bore for the expansion of the fluid.

Fig. 8 is a fragmentary sectional view taken 20 along the line 8—8 of Fig. 9.

Fig. 9 is a fragmentary sectional view taken along the line 9—9 of Fig. 1.

Fig. 10 is a fragmentary sectional view taken 25 along the line 10—10 of Fig. 1.

Fig. 11 is an enlarged fragmentary sectional view taken of the cylinder head.

Fig. 12 is a fragmentary sectional view of the cylinder head within the toroidal bore. 30

Fig. 13 is a perspective view of the cylinder head holder.

Fig. 14 is a sectional exploded view of the fixed member and its cylinder head and the members which define the toroidal bore. 35

Referring now in detail to the drawings, I disclose in Fig. 1 my invention embodied in a rotary engine. My engine is supported upon a base generally designated as A.

More specifically the base or support A is comprised of longitudinally extending members 20, 22 suitably joined by transverse members 24, 26. Upon the transverse member 24, a bearing 28 is located, and in alignment therewith is another bearing 30 mounted upon the transverse member 45 26.

A supporting ring, generally designated as B, has two integrally formed flanges which are supported upon the two longitudinally extending supporting members 20, 22. The supporting ring B 50 has a charging inlet 32 and a discharge outlet 34 therethrough, located on opposite sides of a fixed cylinder head, generally designated as C. An ignition device, such as a spark plug 36, Fig. 10, when an exploding gaseous fuel is to be used is 55

- placed close to the charging inlet. When an explosive fuel is used a mechanically operated check valve must be installed in the intake port. The discharge outlet or exhaust passageway 34 may be directly extended into the atmosphere, or it may be connected to a discharge apparatus muffler (not shown), the type of discharge and inlet apparatus being dependent upon the fuel utilized.
- 10 The fixed cylinder head C is attached to an interior portion of the fixed supporting ring B. The cylinder head C, see Figs. 8, 10, 11, 12 and 14, comprises a small circular disc-like member 38 having a plurality of grooves on its curved bounding surface so that expansible curved rings 40, 41 are fitted therein. The disc-like member 38 is fitted between spaced lugs 44, 45 and held thereto by a polygonal shaped through bolt 46. The lugs 44, 45 are formed integrally with a short arcuate base 48, illustrated in Figs. 10, 11 and 13, and the base sets into a suitable complementary recess in the inner curved surface of the fixed supporting ring B. The base 48 is detachably secured within the recess by tap bolts 50, 51, Figs. 10 and 11.
- 15 The rotor, generally designated as D, see Figs. 1, 8 and 9, is comprised of two hemispherical shells D1, D2. Since each shell is similarly constructed, the details of construction of one shell will suffice 20 since the description of one will apply to the other. The shell D1 has a circumferential rim or flange 54 at its open end extending radially outwardly, and an annular recessed boss 56 extends substantially outwardly at the apex of its closed end.
- 25 A shaft 58, illustrated in Figs. 1, 8 and 9 is fixedly mounted at one of its ends within the recessed boss 56, and the shaft is suitably supported in the bearing 30 for rotation.
- 30 The wall of the shell is suitably tapered to 35 withstand the mechanical stresses and strains imposed thereon, and parallel circular bosses 60, 61 extend on the interior surface of the shell. Exterior bosses 62, 63 are in alignment with bosses 60, 61, respectively, and are located near the recessed boss 56. Similarly located bosses 60A, 61A, 62A, and 63A are formed upon the shell D2. Suitable holes and bores in the bosses provide supports for tie bolts or rods 66, 66 and bearings for rotatable shafts 67, 68, the latter mentioned 40 shafts hereinafter will be further described.
- 35 Interposed between the shells D1, D2 are members, generally designated as E and E1, well illustrated in Figs. 6, 7, and 9, for forming the toroidal bore. Since the members E and E1 are constructed complementary to one another, the details of construction of only one member will be 45 described, since the description will apply to the other. The member E is a disc-like ring member having a flat outer face 69. An inner face 70 has a groove 71 near its curved periphery, designated as 72. On the same face but close to the groove 71 is an arcuate continuous groove 73 which terminates at an edge of the flat face 74. The surface defining the groove functions as part toroidal bore into which the cylinder head C fits. The face 74 terminates at its other edge in the inner curved portion 75 of the member E. The inner circular portion 75 of the member is slightly arcuate as may be seen in Fig. 9.
- 40 A rotary piston, generally designated as G, occupies slots 76 and 76A; slot 76 is in the member E, and slot 76A is in the member E1. The slot 76, of a width slightly greater than the thickness of the piston, extends from a point adjacent

the junction of the face 70 and the groove 73 as one position to a second position diametrically opposite the first position, which is also at a point adjacent the junction of the face 70 and the groove 73.

5 Upon the face 74 is an annular outwardly extending projection 77 which interfits with a complementary recess 78 on face of member E1. In all other details of construction with the exception of the recess 78, the member E1 is similar 10 to member E.

When the members E, E1 are fitted together, face 70 on member E is spaced from a similar face 80 on the member E1. The intervening space is occupied by a tongue 82, Figs. 8, 9, and 14, which 15 is integrally formed with the fixed ring member B. The tongue 82 has a curved inner surface 84 and substantially flat parallel side surfaces 86, 87 which are spaced a distance apart substantially equal to that distance which separates the faces 20 10, 80 of the members E, E1. Upon the surface 86 is an outwardly projecting ridge 88 which interfits in the groove 77, and a ridge 88A similar to the ridge 88 interfits with a complementary groove on the member E1. After the rotor is 25 properly assembled together with the fixed ring B, the curved surface 84 serves as part of the toroidal bore, and the close fit between the surfaces 70 and 86, 80 and 87, and the two sets of interfitting ridges and grooves function to prevent the loss of power from the toroidal bore while in operation.

30 Located within the inner portion of the assembled members E, E1 is a ring-like bushing, generally designated as F, illustrated in Figs. 5 and 35 9. The bushing F has a segmental spherical outer surface 90, which interfits with the complementary bounding surface 75 of the member E, E1. A plurality of radially extending bolts, designated as 89, retain the bushing and the members 40 E, E1 rigidly together. Suitable openings are, also, in the ring-like bushing F for the flange holding bolts 89 and for the passage of the tie rods 66, 66.

45 The circular disc-like piston G, illustrated in perspective in Fig. 3, has three equi-spaced peripheral cut-outs 92, 93, 94 therein, and a series of radially projecting teeth 96 on the inner circular surface. Each cut-out extends from the peripheral edge inwardly a distance so that it 50 clears the inner edge of the abutment rings 40, 41 of the cylinder head and is of a width approximately one time that of the diameter of the cylinder head plus one-third the thickness of the cylinder head. In other words, the size of each 55 cut-out is approximately equal to one time the cylinder bore plus one-third the distance between the inner surface of the lugs 44 and 45. The teeth 96 project radially towards the center of the disc piston G.

60 The piston G is suitably mounted internally of the hemispherical shells D, D1 and passes through the slots 76, 76A at right angles to the plane in which the members E, E1 are located. It is to be observed that in operation the piston G has two 65 motions with respect to the cylinder head C; it simultaneously is rotated about the shafts 58, 58 as one axis and revolves about a changing axis which is always perpendicular to a line joining the shafts 58, 58.

70 The cut-outs 92, 93, 94 are located in the periphery of the piston G so that at a predetermined portion of the cycle of operation the stationary cylinder head C will be located within one of the recesses and upon movement of the piston G to a 75

position away from the cylinder head, as for example, to the position indicated by broken lines G1, Fig. 10, a solid portion of piston G will be wholly within the transverse section of the cylindrical bore formed by the members E, E1 and the surface 84.

If the cut-out portions 92, 93, 94 were not present, the piston would directly impinge upon the cylinder head, thereby rendering the device inoperative.

The piston G is rotatably mounted between supporting guide brackets or plates, generally designated as H, H1, H2 and H3.

Brackets H, H2 are identical in construction, and brackets H1, H2 are identical in construction.

The bracket H, illustrated in Fig. 2, comprises a semi-circular disc-like leg 97 having its straight edge joined at right angles by two flanges 98, 99. A web 100 joins the outer surfaces of the bracket members 97, 98, and the other webs 101, 102 and 103 are also added for strengthening purposes. The flanges 98, 99 are joined to the disc-like rings E, E1 by means of holding bolts or screws, and the free end of the portion 97 is fitted into one of the recesses 105, 105 in the hemispherical shell D. A flat side 106 of the leg portion 97 is located to engage one of the flat surfaces of the piston G.

Complementarily located with respect to the other flat surface of the piston G is the bracket H1, which is constructed similarly to the bracket H, but it has in addition to the legs and webs a bearing 108 in the semi-circular leg portion Fig. 9.

A short shaft 110 is journaled in the bearing 108 and at one end a spur gear 112 is positioned to intermesh with the teeth 96 of the piston G. Upon the other end of the shaft 110 is a bevel gear 114 which is in mesh with another bevel gear 116. The bevel gear 116 is positioned upon the shaft 68 which carries at its other end a spur gear 118. The spur gear 118 meshes with a fixed timing gear 120, the latter being rigidly located upon holding bolts attached to the bearing 30, or the gear 120 may suitably be attached to the transverse member 26. It is obvious that upon rotation of the rotor, the intermeshing of gears 120 and 118 revolves the shaft 68, the bevel gears 116 and 114, the shaft 110, the spur gear 112, and finally the piston G.

A second similar driving gear train connection exists between the stationary gear 120 and the teeth 96 of the piston. The second gear train includes spur gear 122 which is attached to one end of the rotatable shaft 67, and the latter has a bevel gear 126 attached thereto in between the ends of the shaft. The opposite end of the shaft 67 is rotatably mounted in a bearing of the boss integrally formed with the segmental hemispherical shell or casing D2. The bevel gear 126 is in mesh with another complementary bevel gear 128 which is mounted upon one end of a rotatable shaft 130, and mounted upon the other end of the shaft is a spur gear 132 which is in mesh with the gear teeth 96. Thus, the piston G is driven by two gears 112, 132 from two independent gear trains. The two gears balance the driving force imposed upon the piston in order that the piston functions accurately for a long period of time.

The piston is timed to rotate so that one of the openings 92, 93, 94 will interfit with the cylinder head C just at the time that the piston arrives at the cylinder head.

By employing three openings in the peripheral edge of the piston G, the piston is uniformly bal-

anced and the speed of the piston need only be one-third of the speed of the rotor D. Thus, because of the slower speed of the piston, the strain imposed thereon will be reduced.

As the piston G is rotated about the axis formed by a line joining the two bearings 28 and 30, it also revolves in a plane which intersects the above designated axis. The piston, also, revolves about an axis perpendicular to the axis about which the rotor revolves.

Another advantage of using three peripheral openings is as follows:

Assuming a charge of expansive fluid is entering the toroidal bore in the rotor by way of the inlet 32, if the openings in the piston were 180° apart and one of the openings in the periphery of the piston is coincident with the toroidal bore and the cylinder head C, then the second opening would coincide with the toroidal bore thereby allowing a free passage of the expansive fluid from the inlet 32 to the exhaust 34 with the result no turning or driving force would be exerted on the piston. With the openings on the piston positioned 120° apart, as illustrated in Fig. 3, the piston always blocks the toroidal bore cojointly with the cylinder head, thereby presenting a surface to receive the force of the expansive fluid for the entire revolution of the rotor.

The rotor D is assembled so that the bushing F, the disc-like rings E, E1, the brackets H, H1, H2 and H3 and the piston G, as well as the driving gears, form a unit. The unit is assembled in and around the member B and so that the bushing F and other parts are locked in position by virtue of the interfitting inclined curved surfaces 75 and 90 as well as the holding bolts 89, 66, 66.

The member E is held to the shell member D1 by tap bolts 131, 131 through the flange 84, and similar tap bolts 133, 133 hold members D2 and E1 together.

The operation of my invention is as follows:

An explosive charge is introduced through the inlet 32. When an explosive mixture is used, the spark plug 36 will ignite it and the expanding gases will impinge upon the fixed cylinder head C and a solid portion of the rotary piston G. Since the piston G is suitably retained by the members E, E1 and D1, D2 the resultant force will rotate the rotor D. The fluid pressure means can be continuously administered so that the starting and running force will be greatly augmented. A quantity of the expanding gas will at a portion of the cycle of revolution of the rotor D be retained in a portion of the cylindrical bore by two faces of the piston G that are within the bore, this arrangement is necessary, for it is to be remembered that the construction of the piston and the toroidal bore is such that the toroidal bore is never continuously open.

As the expanding fluid impinges on the piston and the piston revolves as well as rotates, the charge pushes the piston past the exhaust opening where the fluid passes into the atmosphere or other suitable exhaust receiver.

The piston G as it approaches the cylinder head has one of its openings 92, 93 or 94 coincide with cylinder head so that the cycle of operation may be repeated.

Of course, the timing gear arrangement revolves the piston G in synchronism with the rotation of the rotor.

My invention may be applied as a stationary motor or it may be applied to drive movable vehicles such as automobiles or aeroplanes. The

motor may be attached to similar motors in tandem arrangement or it may be used singly.

Although my invention has been described in considerable detail, such description is intended 5 as illustrative rather than limiting, as the invention may be variously embodied, and the scope of the invention is to be determined as claimed.

I claim as my invention:—

1. A rotary engine comprising a fixed member, 10 a rotary member located interiorly of said fixed member, a stationary cylindrical cylinder head protruding from said fixed member, a bore in said rotary member into which said cylindrical head protrudes, a piston in said bore whereby an expanding fluid entering said bore by way of said inlet to a portion of said bore between said cylinder head and said piston will exert a force upon the piston to rotate the rotary member, said piston having an opening therein to permit the 15 piston to pass the cylinder head, an inlet passageway for the admission of fluid to said bore, and an exhaust passageway for the egression of the spent fluid.

2. A rotary engine comprising an inlet and an 20 exhaust for the ingress and egress of motivating fluid, a rotor and a cooperable fixed member, said rotor including a toroidal bore, a cylinder head projecting in said bore, said bore partially surrounding said cylinder head, a piston having an 25 opening in its peripheral edge, said piston being rotatably mounted in said rotor and extending through said bore, and means to rotate said piston during the rotation of said rotor.

3. A piston comprising a disc member having 30 an opening at its center, a plurality of internal teeth radially extending into said opening, and a plurality of equi-spaced openings in the periphery of said piston.

4. A rotary engine comprising a fixed ring 35 member, an inlet passageway and an outlet passageway in said fixed member, means for exploding a fluid explosive mixture, a cylinder head extending from the inner surface of said ring member, a rotary member fixed upon two rotatable shafts, said rotary member comprising two 40 hemispherical members, a piston having an opening therein to permit the piston to pass the cylinder head, a pair of disc members having a slot therein for retaining said piston, said piston 45 being adapted to rotate in said slots during the rotation of said rotary member.

5. In a rotary engine comprising a shaft, a set 50 of gears, a rotor rotatably mounted upon said shaft, said rotor having a toroidal bore, a piston located internally of said rotor and arranged to block said toroidal bore, a cylinder head in said bore, said piston being adapted to be rotated by said gears, said piston being movable about an axis within the rotor and also being movable in an 55 axis about which the rotor revolves, and said piston having an opening therein to permit the piston to pass the cylinder head at a predetermined position.

6. A rotary engine comprising an inlet and an 60 exhaust for the ingress and egress of motivating fluid; an annular fixed member; a radially extending cylinder head securely fastened to said annular member; a rotor including a toroidal bore into which said cylinder head protrudes; a 65 disk-like piston having a plurality of peripheral openings and a central opening and projecting into said toroidal bore; a plurality of teeth on the surface defining said central opening; and a synchronous gear mechanism for rotating said

piston, said gear mechanism interposed between a fixed gear on a support member and said teeth on said disk-like piston, and including two driving gears meshing with the said teeth on said disk-like member, said synchronous gear mechanism arranged to provide synchronous operation between the said rotary member and said disk-like piston whereby said piston peripheral openings permit the piston to pass the cylinder head. 5

7. A rotary engine comprising an inlet and an 10 exhaust for the ingress and egress of motivating fluid, a fixed ring-like member, a tongue extending from the central portion of the inner surface of said ring-like member, a rotor adapted to be rotated within said ring-like member, said 15 rotor including a plurality of members having arcuate grooves therein for forming a portion of a toroidal bore, said members having the said tongue protrude therebetween whereby the tongue will complete the surface of the toroidal 20 bore, and means on said fixed member and rotor against which fluid pressure may be applied for rotating the rotor.

8. A rotary engine comprising an inlet and an 25 exhaust for the ingress and egress of motivating fluid, a fixed ring-like member, a tongue extending from the central portion of the inner surface of said ring-like member, a cylinder head extending from the ring-like member, a rotor adapted to be rotated within said ring-like member, said rotor including a plurality of hemispherical shells, an intermediate member to which the said shells are rigidly connected, an incomplete toroidal bore partially surrounding said cylinder head and within said intermediate 30 member, said tongue protruding into the said intermediate member and completing the toroidal bore, said tongue and said intermediate members interfitting, and a piston extending into said toroidal bore and having peripheral openings and 35 being operably connected to said rotor whereby an expansive fluid interposed and exhausted from said bore between the cylinder head and said piston will rotate said piston, said piston being rotatably mounted, and said piston openings permitting the piston to pass the cylinder head. 40

9. A rotary engine comprising an inlet and an 45 exhaust for the ingress and egress of motivating fluid, a fixed ring-like member, a tongue extending from the central portion of the inner 50 surface of said ring-like member, a cylinder head extending from the ring-like member, a rotor adapted to be rotated within said ring-like member, said rotor including a plurality of hemispherical shells, an intermediate member to 55 which the said shells are rigidly connected, an incomplete toroidal bore partially surrounding said cylinder head and within said intermediate member, said tongue protruding into the said intermediate member, and completing the 60 toroidal bore, said tongue and said intermediate members interfitting, and a piston extending into said toroidal bore and having peripheral openings and being operably connected to said rotor whereby an expansive fluid interposed in said 65 bore between the cylinder head and said piston will rotate said piston, said piston being rotatably mounted to rotate with said rotor and also to rotate in a plane transverse to the direction plane in which the rotor revolves, said piston 70 openings permitting the piston to pass the cylinder head, and means to rotate said piston during the movement of said rotor.

10. A rotary engine comprising an inlet and an 75 exhaust for the ingress and egress of moti-

- vating fluid, a fixed ring-like member, a tongue extending from the central portion of the inner surface of said ring-like member, a cylinder head extending from the ring-like member, a rotor adapted to be rotated within said ring-like member, said rotor including a plurality of hemispherical shells, an intermediate member to which the said shells are rigidly connected, an incomplete toroidal bore partially surrounding said cylinder head and within said intermediate member, said tongue protruding into the said intermediate member completing the toroidal bore, said tongue and said intermediate members interfitting, and a piston projecting into said bore and being operably connected to said rotor whereby an expansive fluid interposed in said bore between the cylinder head and said piston will rotate said piston, said piston being rotatably mounted to rotate with said rotor and also to rotate in a plane transverse to the direction plane in which the rotor revolves, said piston having a plurality of equispaced openings in the peripheral edge thereof, each of said openings being adapted to interfit with said cylinder head, and means to rotate said piston in synchronism with the movement of said rotor.
11. A rotary motor comprising a fixed ring-like member, a cylinder head extending from said ring-like member, an inlet and spark plug in said ring-like member on one side of said cylinder head, an exhaust outlet in said ring-like member on the opposite side of said cylinder head, a rotor including a revolvable piston and a bore, said piston having a plurality of peripheral openings and extending into said bore whereby explosive fluid may react upon said cylinder head and said piston, said piston peripheral openings permitting the piston to pass the cylinder head, and means to revolve said piston in synchronism with the movement of the said rotor, the expansive force exerted by an explosive fluid being impressed on said piston for the major portion of a complete revolution of the rotor.
12. A rotary engine comprising a fixed member and a cooperative rotary member, an inlet for the admission of fluid and an exhaust through which the fluid may be discharged, said inlet and exhaust being located in said fixed member, said rotary member including a toroidal bore, a piston in said bore, a cylinder head attached to said fixed member and located within said bore whereby the reaction of the fluid on the piston and cylinder head will move the rotary member, means to rotate said piston about an axis independent of the simultaneous rotation of said rotary member, and said piston having openings therein whereby said piston may pass said cylinder head at predetermined intervals of its independent rotation.
13. A rotary engine comprising a stationary ring-like member and a cooperative rotor, an inlet for the admission of motivating fluid and an exhaust through which said fluid may be discharged, said inlet and exhaust being located in said fixed member, a tongue extending from the central portion of the inner surface of said ring-like member, a cylinder head extending from the ring-like member, a plurality of expansible rings on said cylinder head, a rotor including a plurality of hemispherical shells, an intermediate member to which the said shells are rigidly connected, said intermediate member and said tongue completing a toroidal bore, said bore partially surrounding said cylinder head, a piston mounted at right angles to the plane of and passing through said bore, said piston having a plurality of equi-spaced openings in the peripheral edge thereof, each of said openings being adapted to interfit with said cylinder head and a portion of the piston being within the peripheral bore at all times, and means to rotate said piston in synchronism with the movement of said rotor whereby the fluid may be utilized to move the piston and also to permit the spent fluid to be discharged.

SAMUEL J. COLLUM.
